UNITED STATES PATENT OFFICE.

PAUL B. KLUGH, OF CHICAGO, ILLINOIS, ASSIGNOR TO THE CABLE COMPANY, OF CHICAGO, ILLINOIS, A CORPORATION OF ILLINOIS.

TRACKER-BOARD AND MUSIC-SHEET.

1,205,456.

Specification of Letters Patent. Patented Nov. 21, 1916.

Application filed July 11, 1911, Serial No. 637,973. Renewed November 15, 1913. Serial No. 801,260.

To all whom it may concern:

Be it known that I, PAUL B. KLUGH, a citizen of the United States, residing at Chicago, in the county of Cook and State 5 of Illinois, have invented a certain new and useful Improvement in Tracker-Boards and Music-Sheets, of which the following is a full, clear, concise, and exact description, reference being had to the accompanying 10 drawings, forming a part of this specification.

My invention relates to instruments employing traveling music sheets and tracker boards therefor, such for example as piano 15 players, player pianos and the like.

The invention contemplates a novel form 20 of tracker board having particular advantages and especially useful in connection with a certain type of instrument to be referred to hereinafter.

In the accompanying drawings, Figure 1 is a view of a portion of a music sheet and tracker board embodying my present invention; Fig. 2 is a similar view of a modified 25 form; Fig. 3 is a longitudinal section through one of the sets of ports of the tracker board; and Fig. 4 is a transverse section of the tracker board.

Referring first to Fig. 1, I show a tracker 30 board 1 and a music sheet 2 traveling over the same. The tracker board 1 is provided with apertures or ports 3^a—3^a which are connected together in pairs as shown in Fig. 3, each pair being connected with a 35 duct or channel 7. Apertures or ports 4—4 are arranged in the rear of the apertures 3^a—3^a, an aperture 4 being in the rear of one of the apertures 3^a—3^a of each pair. A 40 pair of apertures 3^a—3^a with an aperture 4 lie in a single note zone.

The music sheet 2 is provided in this form with perforations 5—5 and 6—6. The apertures 5—5 open one of the front perforations 3^a of the various pairs, and the perforations 45 6—6 open the other or associated aperture 3^a of the pairs and also the corresponding or associated rear aperture. The tracker board and music sheet thus set forth can be used in various ways and in connection 50 with various instruments. One very advantageous use would be in connection with the apparatus of Patent No. 899,469, issued September 22, 1908 to Pierce, or in connection with the apparatus of Patent 55 No. 1,183,210 issued May 16, 1916, to myself.

In such case the front apertures 3^a through the channels or ducts 7—7, would be connected with suitable note striking or sound producing apparatus and the rear apertures 4—4 with apparatus or mechanism for modifying the tones or notes produced or sounded. Thus the perforations 5—5 would sound the notes only and the perforations 6—6 would not only sound the notes but would modify the same as well, making the 60 same softer or louder as desired. If made louder the perforations 6—6 would have the effect of being solo perforations.

In Fig. 2, I show the same tracker board 1 but a different form of music sheet 2^a. 70 In this music sheet there are perforations 5—5, as before, and there are also perforations 6^a—6^a which are relatively wide and so open not only the rear apertures 4—4 but both of the corresponding front apertures 3^a—3^a; instead of only one of the latter as in the foregoing modification. 75

It will be understood that changes and modifications can be made without departing from the invention.

What I claim is:

1. A tracker having a plurality of ports side by side for a single note, and channels uniting said ports into a single unobstructed passage, and another port in transverse 85 alignment with one of the first named ports for modifying the action of the same note sounding mechanism.

2. A tracker having a double aperture therein and an elongated aperture in the 90 rear of part of the double aperture, for modifying the action of the same note sounding mechanism, the parts of said double aperture being connected together.

3. A tracker having a double aperture 95 therein, and an aperture for modifying the action of the same note sounding mechanism, coöperating with said first named aperture in such a position in said tracker that said last named aperture is opened before 100 said first named aperture, the parts of said double aperture being connected together.

4. The combination of a tracker having a plurality of ports for the same note arranged at the side of one another lengthwise of the tracker and also having a port for modifying the action of the same note sounding mechanism in the rear of one of the aforesaid ports, and a music sheet hav- 110

ing perforations some of which are adapted to open one of the aforesaid plurality of ports and the port in the rear thereof and others of which are adapted to open another 5 of said plurality of ports.

5. A tracker having a plurality of ports side by side longitudinally of the tracker, and channels uniting said ports into a single unobstructed passage, and another port 10 in transverse alinement with one of the first named ports for modifying the action of the same note sounding mechanism as the first named ports.

6. A tracker having double apertures 15 whereof each double aperture lies in a single note zone and whereof the two parts of each double aperture are connected together, said tracker also having an aperture in the rear of one part of each of said double apertures, 20 in combination with a music sheet having narrow perforations, each for opening one part of a double aperture and the aperture in the rear thereof, and other narrow perforations, each for opening only one part 25 of a double aperture.

7. A tracker having a plurality of ports arranged in note zones, a single note zone comprising a plurality of ports arranged side by side longitudinally of the tracker, 30 channels uniting said ports, and another port in transverse alinement with one of the first named ports.

8. A tracker having a plurality of ports arranged in note zones, a single note zone 35 comprising a plurality of ports arranged side by side longitudinally of the tracker, channels uniting said ports, and another port in transverse alinement with one of the first named ports, in combination with a 40 music sheet having narrow perforations for opening one of the first named ports and the port in transverse alinement therewith and other narrow perforations for opening the other of the first named ports.

45 9. A tracker having a series of ports arranged in line lengthwise of the tracker, said ports being arranged in groups, and a second series of ports transversely displaced with reference to the first mentioned series, 50 there being a port in said second series for each group of ports in the first mentioned series.

10. A tracker having a series of apertures arranged lengthwise of the tracker in 55 alinement with one another, there being two apertures for each note, and a second series of apertures transversely displaced with reference to the first mentioned series, there being one aperture for each note in said second series.

60 11. A tracker having a series of alined apertures extending lengthwise of the tracker, there being two apertures for each

note, and a second series of apertures in the rear of said first named series, there being 65 one aperture for each note in said second series.

12. A tracker having a series of alined apertures extending lengthwise of the tracker, there being two apertures for each 70 note, and a second series of apertures in the rear of said first named series, there being one aperture for each note in said second series, which said aperture is in transverse alinement with one of the apertures of said 75 first named series.

13. A tracker having a series of ports arranged in line lengthwise of the tracker, 80 said ports being arranged in pairs, and a second series of ports transversely displaced with reference to the first series, there being a port in said second series for each pair of ports in the first series.

14. A tracker having a series of ports arranged in line lengthwise of the tracker, 85 said ports being arranged in pairs, and a second series of ports transversely displaced with reference to the first series, there being a port in said second series for each pair of 90 ports in the first series, said port in said second series being in transverse alinement with one of the ports of the pair of ports with which it is associated.

15. A tracker having a group of ports comprising a plurality of ports arranged 95 side by side lengthwise of the tracker and connected with one another, and another port transversely displaced with reference to said plurality of ports.

16. A tracker having a group of ports comprising a plurality of ports arranged 100 side by side lengthwise of the tracker, and another port transversely displaced with reference to said plurality of ports, said transversely displaced port being in transverse alinement with one of said side by side 105 ports.

17. A tracker having a group of ports comprising a pair of ports arranged in alinement with one another longitudinally of 110 the tracker and connected with one another, and a third port transversely displaced with reference to said pair of ports.

18. A tracker having a group of ports comprising a pair of ports arranged in 115 alinement with one another longitudinally of the tracker, and a third port transversely displaced with reference to said pair of ports, said third port being in transverse alinement with one of said pair of ports. 120

In witness whereof, I hereunto subscribe my name this 7th day of July A. D., 1911.

PAUL B. KLUGH.
